BURNER

Frank A. Stoll, Detroit, Mich., assignor to Detroit Lubricator Company, Detroit, Mich., a corporation of Michigan

Application September 20, 1935, Serial No. 41,338

7 Claims. (Cl. 158—115)

My invention relates generally to heating systems and more particularly to pilot light burners therefor.

In heating systems of the type which employ a gas burning pilot light for lighting the main burner, it frequently occurs that the pilot light is accidentally extinguished. This is usually caused, as is well known, by the explosion or puff following the extinguishment of the main burner, or by back drafts from the chimney. The accidental extinguishment of a gas burning pilot light is, of course, objectionable chiefly because of the liable danger to life and damage to property resulting from the escape of gas. Usually heating systems are provided with safety devices operable for stopping flow of gas to the main burner in the event of extinguishment of the pilot light, but many of such devices do not also stop flow of gas to the pilot light. In any event, frequent extinguishment of the pilot light is objectionable because of the resultant inefficient operation of the heating system and also because of the inconvenience of relighting the pilot light.

It is therefore one of the objects of my invention to provide a new and novel pilot light burner for lighting a main burner in a heating system and one in which the above mentioned objectionable features are obviated.

Another object of my invention is to provide a gas burner so constructed that accidental extinguishment of its flame is prevented.

Another object of my invention is to provide a pilot light burner having a burner outlet for a gas flame for lighting another burner and which is automatically relighted in the event it becomes accidentally extinguished.

Another object of my invention is to provide a pilot light burner of the above mentioned character which is simple in construction and economical to manufacture.

In the accompanying drawing, to be taken as a part of this specification, I have fully and clearly illustrated my invention, in which drawing—

Figure 1 is a view in side elevation of an apparatus embodying my invention but with the pilot burner in vertical central section;

Fig. 2 is a top plan view of the pilot burner;

Fig. 3 is a detail view of the pilot burner shown in elevation and partly broken away to show internal construction, looking from right to left of Fig. 1;

Fig. 4 is a view showing an apparatus embodying a modified form of my pilot light burner in vertical central section, and

Fig. 5 is a view showing an apparatus embody-

ing still another form of my invention and with parts in vertical central section.

Broadly, my invention resides in the provision of a gas burner in which the novel construction includes means for preventing the accidental extinguishment of the burner flame. It is well known that when a gas flame is extinguished by a disturbance in the air or medium immediately surrounding the burner, the gas issuing from the burner outlet frequently is driven back into the burner outlet port, with the result that the flame is smothered therein because of lack of proper combustible mixture. In my invention although the gas may be driven back into the burner by sudden changes of pressure immediately adjacent the burner, provision is made to maintain a shielded flame to reignite the pilot burner upon cessation of the disturbance.

Referring now to the drawing, and more particularly to Figs. 1, 2 and 3 thereof, the pilot burner shown in these views includes a tip, or terminal member 1 to which gas is supplied for issuance therefrom, the tip preferably being a conduit of tubular form, or pipe-like, as shown. The tubular tip member 1 is preferably disposed with its longitudinal axis extending vertically, the upper end of the tip member preferably being closed, as at 2. Gas is supplied to the tip member 1 through an elbow fitting 3 in which the open lower end of the member 1 is supported and sealed as by screw-threaded connection thereto. The fitting 3 is fed by a supply pipe or line 4 from the usual source of fuel supply (not shown).

In order to provide a gas burner which is efficient in operation and one in which the flame will not be accidentally extinguished by surrounding disturbances, I provide the tip member 1 with a plurality of gas outlets 5 and 6 and provide a shield member 7 which surrounds or houses a portion of the tip member 1, with the shield member side wall in spaced relation thereto, and which encloses the outlets 5 and 6. The outlets 5 and 6 are preferably located in the vertical side wall of the tip member 1, intermediate its ends, the outlets 5 preferably being larger than the outlets 6. There are four of the larger outlets 5, in the present instance, and these outlets are preferably disposed and arranged in diametrically opposite pairs in spaced, vertical alignment. The outlets 6, or smaller outlets, of which there are eight in this instance, are also preferably disposed and arranged in spaced, vertically aligned groups of four and are preferably diametrically opposite each other and spaced equally or at 90° from the larger outlets 5, as shown.

The shield or trap member 7 is preferably a cap-like member of tubular form having an open lower end 7^a and may be constructed of sheet metal, if desired. The upper end of the tubular shield member 7 is closed by an end wall 8, and in the end wall 8 there is provided a centrally disposed aperture 8^a for receiving the tip member 1 which extends therethrough having an upper end portion projecting exteriorly of the shield. The upper end wall 8 is preferably conical in form, extending upwardly and inwardly converging from the periphery of the side wall to the centrally disposed aperture 8^a through which the tip member 1 extends. An upper end portion of the tip member 1 may be of reduced diameter to provide an upwardly facing annular shoulder or seating surface 8^b for supporting the shield member 7. The shield member 7 may be press-fitted, welded, or otherwise suitably secured and sealed against leakage to the tip member.

The inner wall of the shield member 7 cooperates with the outer wall of the tip member 1 to provide an annular gas chamber or reservoir 10 in which gas issuing from the outlets 5 and 6 is trapped. Gas issues from the reservoir 10 from a plurality of apertures 11 in the top wall 8, these apertures constituting the burner outlets and also issues from the open shield end 7^a. The burner outlets 11 are oppositely disposed, there being two of such outlets in the present instance, and preferably the burner outlets 11 are located in the same vertical plane with the gas outlets 5 of the tip member 1, the outlets 5 preferably being in the upper portion of member 1 and adjacent the outlets 11. Preferably the combined capacities of the outlets 11 is less than the combined capacities of the outlets 5 and 6 so that gas will be trapped in the reservoir 10 and rising will tend to escape from the relatively small and flow-restricting burner outlets 11 with excess gas escaping from the open end 7^a. The downwardly facing end of the shield member 7 is open, as at 7^a as above noted, to surrounding atmosphere, this opening being relatively large compared to the burner outlets 11 so that any transient pressure change acting on the open end of the reservoir 10 will exert a greater force on the gas in the reservoir than the force exerted on the gas by the pressure change acting through the relatively small outlets 11. Through the side wall of the upper end portion of the tip member 1, and externally of the shield member 7 and above wall 8, there is provided a plurality of laterally extending, radially spaced apertures or orifices 13 which constitute other burner outlets. The burner outlets 13 are disposed adjacent the burner outlets 11, some of the outlets 13 being in the same vertical plane with the outlets 11. The pilot light burner may be arranged adjacent a main burner, designated at 14, for lighting the same upon issuance of gas therefrom.

In the operation of the apparatus above described, the gas issuing from the burner outlets 11 which form the pilot 13 and is lighted, and the flames of the burner outlets 13 which discharge laterally are employed for lighting a main burner, or burners, while the flames from the burner outlets 11 act to light the gas issuing from burner outlets 13 in the event that the flame thereof becomes extinguished. When pressure disturbances occur in the fire box, or surrounding the pilot burner, such as a rush of air caused by the puff following the extinguishment of the main burner or by a back draft from the chimney, the

flame of outlet burners 13 may be extinguished. In case of a sufficient disturbance to extinguish the flames issuing from orifices 11 and 13, the flame which is burning at the lower end of shield 7 may be driven up inside of shield 7 and will, upon cessation of the disturbance, return to the open shield end 7^a and burn up around the outside wall of the shield to reignite the jets of gas issuing from said orifices 11 which will in turn reignite the gas from the main burner lighting 10 orifices 13. The orifices 5 are positioned below and in a vertical plane with orifices 11 so that the fuel issuing from the orifices 5 is fed substantially directly beneath and for discharge through the orifices 11. The orifices 6 are positioned intermediate the orifices 11 so that the probability of extinguishment of the flame at orifices 6 and within chamber 10 upon inward draft through orifices 11 will be substantially eliminated.

The burners shown in Figs. 4 and 5 are similar in construction to the previously described burners and therefore, like characters of reference are employed to designate like parts.

The burner shown in Fig. 4 differs from the previously described burner in that it does not have the burner outlets 13 for lighting the main burner 14, but instead employs the flame of the burner outlets 11 to light the main burner. In Fig. 5 there is shown a gas burner lighting system which comprises a pilot light burner or tip member 1 arranged to 30 light a main burner 14, and a second pilot light burner which includes a tip member 1', the second burner being arranged adjacent the burner 1 for lighting the same in the event its flame becomes accidentally extinguished. In this construction the burner 1 and the second pilot burner are separate structures instead of being combined in a single unit, as in the burner shown in Figs. 1, 2 and 3. The burner or tip member 1 differs from the first described burner or tip member in that it does not have the outlets 5 and 6, and the shield 7, while the burner 1' differs from the first described burner 1 in that it does not have the burner outlets 13.

What I claim and desire to secure by Letters Patent of the United States is:

1. A pilot burner comprising a tubular member for connection to a source of gas supply, a member closed at its upper end and open at its lower end to provide a gas discharge orifice and surrounding a portion of said tubular member, said last-named member having a burner orifice above said lower end, said tubular member having an outlet orifice discharging within said last-named member, said outlet orifice having a greater flow capacity than said burner orifice so that excess gas will issue from said discharge orifice for ignition external of said closed member whereby a flame is maintained for reignition of the gas issuing from said burner orifice.

2. A pilot burner comprising a tubular member for connection to a source of gas supply, a shield member having an end wall and supported by said tubular member and housing a portion of said tubular member, said shield member having a burner orifice in said end wall and having an open lower end to provide a gas discharge orifice below said burner orifice, said tubular member having an aperture through its side wall within said shield member for supplying gas to the interior of said shield member and to said orifice, said burner orifice having a flow capacity less than the flow capacity of said tubular member aperture so that gas will issue from said discharge orifice for ignition external of said shield

- member whereby a flame is maintained for reignition of the gas issuing from said burner orifice.
3. A pilot burner comprising a tubular member for connection to a source of gas supply, a shield member having an end wall with an aperture therethrough, said aperture receiving said tubular member, said shield member having a burner orifice in said end wall and having an open lower end to provide a gas discharge orifice below said burner orifice, said tubular member having an aperture through its side wall within said shield member for supplying gas to the interior of said shield member and to said orifices, said burner orifice having a flow capacity less than the flow capacity of said tubular member aperture so that gas will issue from said discharge orifice for ignition external of said shield member whereby a flame is maintained for reignition of the gas issuing from said burner orifice.
- 20 4. A pilot burner comprising a tubular member having an end wall and an open end for connection to a source of gas supply, a cylindrical hollow shield member having a converging end wall with a central aperture therethrough, said tubular member extending through and tightly fitting in said aperture with said end walls in spaced relation, said tubular member having an aperture in its side wall within said shield member and adjacent said shield member end wall, 25 said shield member end wall having an aperture therethrough positioned above said side wall aperture so that gas issuing from said side wall aperture will be supplied substantially directly beneath and for discharge through the aperture in said shield member wall, said tubular member having an aperture in its side wall adjacent the lower end portion of said shield member to supply gas to the interior of said shield member, said tubular member apertures having a capacity 30 greater than the flow capacity of the aperture in the shield member end wall so that gas will issue from the lower open end of said shield member, said tubular member having a side wall aperture intermediate said end walls and positioned relative to said shield member aperture for ignition of the gas issuing from said last-named side wall aperture.
- 45 5. A pilot burner comprising a tubular member having an end wall and an open end for connection to a source of gas supply, a cylindrical hollow shield member having a converging end wall with a central aperture therethrough, said tubular member extending through and tightly fitting in said aperture with said end walls in spaced relation, said tubular member having a plurality of longitudinally aligned apertures in its side wall within said shield member end wall, said shield member end wall having an aperture therethrough positioned
- above said side wall aperture so that gas issuing from said side wall aperture will be supplied substantially directly beneath and for discharge through the aperture in said shield member wall, said tubular member having a plurality of longitudinally spaced apertures extending from the lower end portion of said shield member to a point intermediate the first-named side wall apertures to supply gas to the interior of said shield member, said tubular member apertures having a capacity greater than the flow capacity of the aperture in the shield member end wall so that gas will issue from the lower open end of said shield member, said tubular member having a side wall aperture intermediate said end walls and positioned relative to said shield member aperture for ignition of the gas issuing from said last-named side wall aperture.
6. A pilot burner comprising a tubular member for connection to a source of gas supply, a shield member having an end wall with an aperture therethrough, said tubular member extending through said aperture and having a portion external of said shield member end wall, said external portion having a burner orifice, said shield member having an open lower end to provide a gas discharge orifice below said burner orifice, said tubular member having an aperture through its side wall within said shield member for supplying gas to the interior of said shield member so that gas will issue from said discharge orifice for ignition external of said shield member whereby a flame is maintained for reignition of the gas issuing from said burner orifice.
7. A pilot burner comprising a tubular member for connection to a source of gas supply, a shield member having an end wall with an aperture therethrough, said shield member end wall having a burner orifice, said tubular member extending through said aperture and having a portion external of said shield member end wall, said external portion having a burner orifice for ignition by the flame from said first-named burner orifice, said shield member having an open lower end to provide a gas discharge orifice below said shield member burner orifice, said tubular member having an aperture through its side wall within said shield member for supplying gas to the interior of said shield member and to said shield member burner orifice and said discharge orifice, said shield member burner orifice having a flow capacity less than the flow capacity of said tubular member aperture so that gas will issue from said discharge orifice for ignition external of said shield member whereby a flame is maintained for reignition of the gas issuing from said shield member burner orifice.

FRANK A. STOLL.
